MATHIAS U. McFEELY AND MICHAEL ANDRASHAK, OF HEILWOOD, PENNSYLVANIA.

DERAILER.

Application filed June 28, 1926. Serial No. 119,125.

The object of this invention is the provision of a block for derailing runaway cars on mine or other tracks, which block is characterized by simplicity in construction and reliability and efficiency in practical use.

To the attainment of the foregoing, the invention consists in the improvement as hereinafter described and definitely claimed.

10 In the drawings:

Figure 1 is a plan view showing the improvement in applied position.

Figure 2 is a side elevation thereof.

15 Figure 3 is a sectional view on the line 3—3 of Figure 2.

The derailing block is wholly constructed of metal and is of a desired length and width. The block includes a central portion which I will term a body 1. The body 20 has a down turned flange merging into an inwardly directed lip 2. This forms the body with a rail engaging head. The flat under face of the body rests on the top of a rail 3. The top of the body is arched, as at 4, and the inner face of the body is formed with an upstanding flange that provides guides for the rail. The flange is of a greater length than the body, and the said flange, from the center thereof, is inclined outward 25 30 ly from the body in opposite directions, as indicated by the numerals 5 and 6, respectively. The ends of the flange provided with the inclined faces 5 and 6 are formed with outwardly extending flanges in the 35 nature of arched planes 7, respectively, which merge into the rounded wall 4 of the body 1. The angle flanges 5 and 6 are connected by an outer web 8, and this web is formed with an aperture 9 to afford a hand 40 hold whereby the block may be easily carried and quickly arranged on a rail. The

body, opposite its hooked edge 2, has its opposite edge, flanged downwardly to provide the same with an angle lip 10, and this lip is adapted to be arranged on the 45 opposite side of the head of the rail to that engaged by the hook 2.

When the device is positioned as shown in Figure 1 of the drawings, it will be apparent that the wheels of the car approaching the block in either direction will contact with either of the angle walls 5 or 6 of the flange and be guided thereby off of the rail. By this simple construction and arrangement of parts any disastrous accidents to runaway cars or trains will be avoided. The device, while of metal, is of a light construction and may be easily carried, positioned and removed by a single hand.

Having described the invention, we claim:

A derailing block including a body whose upper face is arched, and whose outer face is formed with an inwardly directed lip forming a rail engaging hook, said body having its rear formed with a downwardly directed inclined lip and the top of the body being flanged upwardly, said flange having its inner face, from the center thereof, inclined outwardly in opposite directions, said flange being of a greater length than that of the body and having outwardly extending parts providing arched planes which merge into the rounded face of the body, a web connecting the angle portions 70 75 of the flange and said web having an opening therethrough to provide a hand grip.

In testimony whereof we affix our signatures.

MATHIAS U. McFEELY.
MICHAEL ANDRASHAK.
